Primary Examiner — Mark A Goodwin(74) *Attorney, Agent, or Firm* — BERESKIN & PARR
LLP/S.E.N.C.R.L., s.r.l.(57) **CLAIM**

The ornamental design for a stump harvester, as shown and described.

DESCRIPTION

FIG. 1 is a front perspective view of a first variant of a stump harvester with jaws in a first, closed position;

FIG. 2 is a rear perspective view of the stump harvester of FIG. 1;

FIG. 3 is a left side view of the stump harvester of FIG. 1;

FIG. 4 is a right side view of the stump harvester of FIG. 1;

FIG. 5 is a front view of the stump harvester of FIG. 1;

FIG. 6 is a rear view of the stump harvester of FIG. 1;

FIG. 7 is a top view of the stump harvester of FIG. 1;

FIG. 8 is a bottom view of the stump harvester of FIG. 1;

and,

FIG. 9 is a rear perspective view of the stump harvester of FIG. 1, showing the jaws in a second, open, position.

The broken lines shown in the drawings are for illustrative purposes only and form no part of the claimed design.

1 Claim, 9 Drawing Sheets---
